COMBINED TOOTHBRUSH HOLDER AND TIMER

John F. Berardo, Arcadia, Calif.
(8727½ La Tijera Blvd., Los Angeles, Calif. 90045)

Filed Aug. 1, 1968, Ser. No. 12,997

Term of patent 14 years

Int. Cl. D6—01

U.S. Cl. D33—28

FIG. 1.

FIG. 2.

FIG. 3.

FIG. 4.

FIG. 1 is a front elevational view of a combined toothbrush holder and timer embodying my new design;

FIG. 2 is a side elevational view thereof;

FIG. 3 is a rear elevational view thereof; and

FIG. 4 is a top plan view thereof.

The broken line representation of a toothbrush in FIGS. 1 and 2 is for purposes of illustration only.

I claim:

The ornamental design for a combined toothbrush holder and timer, substantially as shown and described.
